UNITED STATES PATENT OFFICE.

WILLIAM J. RUFF, OF QUINCY, ILLINOIS.

FIRE EXTINGUISHER.

Application filed September 22, 1918. Serial No. 325,306.

To all whom it may concern:

Be it known that I, WILLIAM J. RUFF, a citizen of the United States, and a resident of Quincy, in the county of Adams and State of Illinois, have invented certain new and useful Improvements in Fire Extinguishers, of which the following is a specification.

My invention relates to fire extinguishing apparatus and is adapted particularly for use in aerial vehicles and other places where considerable movement or motion of the parts to be protected are found.

One object of my improvement is the provision of simple and efficient means for automatically putting out small fires before they obtain headway.

A further object is the provision of signaling apparatus for indicating fires.

20 A still further object is the provision of a simple and efficient means for applying fire extinguishing fluids to a fire.

Another object is the provision of simple and efficient means for forcing a fire extinguishing fluid under pressure into a fire extinguishing liquid under circumstances where the apparatus may be turned in any direction.

Other objects will appear hereinafter.

30 An embodiment of my invention is illustrated in the accompanying drawings forming a part of this specification and in which,

Fig. 1 is a view showing more or less diagrammatically fire extinguishing apparatus embodying my invention.

Fig. 2 is a longitudinal section of a tank used in the construction.

Fig. 3 is a section taken on line 3—3 in Fig. 2.

40 Fig. 4 is a fragmental section showing a modified form of the parts in the tank shown in Fig. 2, and

Fig. 5 is a side view of a nozzle-handle and spray-forming plate used in the construction.

Referring more particularly to the drawings, I have indicated more or less diagrammatically in Fig. 1, my fire extinguishing apparatus which is particularly applicable to aeroplanes and other aerial vehicles where the apparatus is apt to be turned in any direction. In fire extinguishing apparatus for aeroplanes and the like, it has been found that the apparatus which requires to be pumped by hand, or otherwise requiring the use of both hands of the operator, are of

comparatively little use, since the operator's attention must be divided between the fire fighting apparatus and the manipulation of the aeroplane or the like.

I have not shown my apparatus as applied to an aeroplane, but it will be apparent to those skilled in the art, that the different parts may be attached to the aeroplane in desired positions or any desired manner from the description herein.

I prefer to use carbonic acid gas under high pressure to extinguish small fires and as a means for forcing the fire extinguishing liquids into contact with larger fires. In Fig. 1 I have indicated a tank 5 which may be any desirable form of container for containing the carbonic acid gas under high pressure. The tank 5 is shown as having a valve 6 at its top for controlling the passage of the fluid from said tank. Valve 6 is intended to represent any suitable valve for this purpose.

In my device, I desire to provide automatic means for spraying the carbonic acid gas directly onto a fire as soon as such fire is started. For this purpose I connect a pipe 7 with a suitable discharge nozzle 8 which has fusible means therein adapted to be fused by the heat from a small fire and permit the escape of the fluid from such device. The member 8 may represent a sprinkler head now on the market or any other form of fusible nozzles. In use, as many of such nozzles as may be desired may be used and in any desired position about the aeroplane or the like, such as adjacent the gas tank, carburetor, engine or other places, none of which are shown, as those skilled in the art will know how to apply such devices.

In the pipe 7 I connect a whistle 9 or other alarm means by which an operator will be notified that a fire has fused one of his members 8, in which instance he will then operate the other part of the apparatus to be described later.

I have shown a means for operating the whistle which consists of a chamber 10 having a diaphragm 11 therein with a valve stem 12 connected to the diaphragm and attached to a valve 13 for controlling the flow of fluid to the whistle 9. On the side of the diaphragm 11 opposite stem 12 I have indicated a compression spring 14. The arrangement is such that when the pressure of tank 5 is on the pipe 7 and the member 8 is closed, the pressure will hold the diaphragm 11 in a po-

sition to maintain the valve 13 closed, and when member 8 has been fused so as to permit the escape of fluid therefrom, the pressure in the pipe 7 will be somewhat reduced, and this will permit the spring 14 to press the diaphragm toward the valve 13 and open the latter sufficiently to permit the gas to blow the whistle 9.

In the pipe 7, adjacent the valve 6, I have indicated a three-way valve 15. In the position shown this valve 15 conducts the fluids from valve 6 into pipe 7 and it is intended to keep the valve 15 in this position when there are no fires. When the whistle 9 has indicated that there is a fire, the operator turns valve 15 so that the passage therethrough conducts pressure from tank 5 into pipe 16 and from pipe 16 through a regulating valve 17 which may be set to operate at any desirable pressure.

In a tank 18 I provide a fire extinguishing liquid which may be any of the numerous fire extinguishing liquids on the market, but I prefer to use liquids which are suitable for putting out gasoline fires or the like. Such liquids often contain in the combination, carbon tetra chloride and ethyl benzoate in solution, or which contain carbon tetra chloride and anilin. The tank 18 may contain any desirable quantity of this liquid, but I preferably fill the tank to an extent to leave a gas space at the top of the liquid. The pipe 16 is connected with the tank 18 and has passages 19 which lead from said pipe 16 into the interior of tank 18. Where the liquid is above the openings of passages 19, the gas will bubble up to the top of liquid 20 in said tank and remain at the top of such liquid.

In the tank 18 I provide a discharge member 21 which in the present instance comprises a pipe 21 journaled at one end in a bearing block 22 and with its other end in a fitting 23, the bearings 22 and 23 being secured to the tank in any desirable manner. In the present form I have indicated a conical seat 24 in the fitting 23 with a member 25 attached to the tube 21 and seated in said conical seat 24. A spring 26 presses between bearing member 22 and a flange 27 on the pipe 21 so as to maintain the member 25 against its seat 24. By grinding or otherwise fitting the member 25 in its seat a substantially fluid-tight joint is formed which will turn easily in use.

Depending from the pipe member 21 are weights 28 and 29. A passage 30 leads through each of the weights 28 and 29 from the bottom portion of tank 18 to the interior of tube 21 so that the liquid 20 may pass up through said passages into the tube 21 and out through the latter into a pipe 31. In each of the passages 30 is a valve seat 32 which cooperates with a valve 33. The valves 33 are connected together by a stem 34

and the latter is of such length that only one valve 33 will be seated at one time. The arrangement is such that when the tank 18 is moved so that one end rises an appreciable distance above the other, the weight of valves 33 and stem 34 will cause such valves and stem to slide longitudinally of the stem and close the valve which is uppermost and open the valve which is lowermost. As often as either end of the tank is elevated above the other, these valves will move as just described so that only the lowermost opening 30 will conduct fluid to pipe 31.

With this arrangement it will be apparent that the weight members 28 and 29 will always hold the lower ends of the passages 30 adjacent the lower side of tank 18 regardless of any rotary movement given to tank 18; also the valves 33 and their stem 34 will cause the uppermost of passages 30 to be closed. With this arrangement then the gas pressing on liquid 20 can only force such liquid to leave the bottommost part of tank 18 into the pipe 31. This prevents the gas from being blown through the device without passing through the liquid.

In Fig. 4, I have shown a slightly modified form of weight member and mounting of the spring 26. Gas leaving pipe 16, in this form, would pass directly into the open end 35 of the discharge member 21 and downwardly through a passage 36 to the bottom of liquid 20 then bubble up through said liquid to the top of the latter to exert force on the top of such liquid. In this form it is desirable to provide a small baffle plate 37 between the opening of passage 30 and passage 36 to prevent a portion of the gas passing directly into the passage 30.

Also, in Fig. 4 the spring 26 is mounted outside the tank 18 with a cover 38 attached to the tank in a manner so that it can be removed to inspect or repair the spring or its mounting should such a thing be desirable.

To the pipe 31 is connected a pipe 39, shown as broken off, which is designed to connect with a distributing system such as set forth in my companion application, U. S. Serial No. 294,105, filed May 1, 1919.

Also connecting with the pipe 31 is a hose 40 which may be placed in any desirable position about the aeroplane or the like, but preferably in a position to be readily accessible to the operator so that he can with one hand grasp the handle 41 of a nozzle 43 and direct the fire extinguishing fluids to places where the fire is burning. Any form of nozzle 41 may be utilized, but I prefer to use one in which a flexible plate 42 is secured to one side of the handle 41, so that the operator can flex the plate 42, as indicated by dotted lines in Fig. 1, to change a stream issuing from nozzle 43 into a spray by simply pressing the plate 42 into the path of

such stream. It is understood that any and all of the valves shown may be connected in such a way, or positioned in such places, that they will be easily accessible to an operator for manipulation.

In Fig. 1 the device is arranged so that the full pressure of tank 5 is on pipe 7 and nozzle 8, but a reducing valve of any suitable design may be placed in pipe 7, or reducing valve 17 may be placed in pipe 7 adjacent valve 6 to reduce the pressure of gas to nozzle 8 and whistle 9 as well as to tank 18.

In use, the tank 18 is filled half full or more with a fire extinguishing fluid and the tank 5 charged with carbonic acid gas, or the like. The valve 6 is left open and valve 15 left in the position indicated in Fig. 1 under normal conditions so that when a fire occurs adjacent the member 8 and the seal is broken in the latter, gas from tank 5 can pass through the member 8 to put out small fires. When member 8 opens the pressure in pipe 7 will be reduced and this permits the spring 14 to open the valve 13 slightly to operate the whistle 9. This directs the attention of the operator to the fire and he immediately moves valve 15 so as to direct the gas from cylinder 5 through the regulating valve 17 to tank 18 where the gas forces the fire extinguishing fluid out through pipe 31 to nozzle 41 which is directed toward the fire by the operator as desired. It will be apparent, of course, that the valves in pipe 31 are opened to permit the gas to pass to said nozzle.

I have described my device as being particularly adapted for aerial vehicles, but it may be used on automobiles, boats, trains and other vehicles, or in buildings, or wherever fire extinguishing apparatus is desirable.

I claim:

1. A fire extinguisher comprising a substantially cylindrical tank having a seat at one end thereof; a pipe pivoted at the axis of said tank; a member at one end of said pipe engaging said seat; a spring engaging the other end of the pipe and tank holding said member against said seat forming a fluid-tight joint; and hollow weights extending laterally from said pipe and having openings therethrough extending from the interior of said pipe to adjacent the inner wall of the tank at the ends of the latter.

2. A fire extinguisher comprising a tank; a weighted member pivoted in the tank with a portion adjacent the bottom of said tank, there being feed and discharge passages in said weighted member with their respective openings spaced apart in said portion of the weighted member; and a baffle plate on said member between said openings.

3. A fire extinguisher comprising a substantially cylindrical tank; a bearing at one end of the tank having a discharge opening

for the tank therethrough and a seat around said opening; a pipe journaled in the bearing; an enlarged member on the pipe engaging and fitting said seat; resilient means pressing the pipe longitudinally thereof to hold the member against said seat; and hollow members extending from said pipe to adjacent the interior lateral wall of said tank.

4. A fire extinguisher comprising a container; bearings at the ends of the container, there being a discharge opening through and a conical seat in one of said bearings; a discharge pipe journaled axially of the tank in said bearings; a member on said discharge pipe engaging said conical seat; and resilient means pressing said member into said seat forming a fluid-tight joint.

5. A fire extinguisher comprising a container; bearings in the container, one of said bearings having a discharge opening therethrough and a conical seat therein; a pipe disposed substantially axially of the container and journaled in said bearings; weight members on the pipe with openings therethrough leading from the bottom of the tank to the interior of said pipe; an enlarged conical member on the pipe seated in said conical seat; and a spring engaging said pipe and adapted to hold said conical member against said seat.

6. A fire extinguisher comprising a tank adapted to contain a liquid; a discharge nozzle; pipes connecting said tank with said discharge nozzle; a source of gas under pressure connected with said pipes; a reducing valve in said pipes; a three-way valve adapted to alternately connect the source of gas under pressure with the nozzle and to connect the source of gas under pressure with said tank; alarm means connected in said pipes adapted to cause an alarm when gas is issuing from said nozzle; and means in said tank for utilizing pressure of gas for forcing liquid out of said tank regardless of which portion of the tank is uppermost.

7. A fire extinguisher comprising a tank adapted to contain a fire extinguishing fluid; a nozzle; a source of gas under pressure; and a three-way valve connected with the tank, nozzle and source of gas under pressure adapted to alternately connect the source of gas under pressure with said tank and said nozzle; discharge means connected with said tank; and means in said tank for utilizing the pressure of gas for forcing liquid out of said tank.

8. A fire extinguisher comprising a tank adapted to contain a liquid; a nozzle; a source of gas under pressure; pipes connecting said nozzle, tank and source of gas under pressure; a valve in said pipes adapted to control the flow of gas from said source of gas supply alternately to the tank and nozzle; discharge means connected with said tank

and an alarm in said pipes operable by reducing the pressure of gas in said pipes below a predetermined pressure.

9. A fire extinguisher comprising a tank 5 adapted to contain a liquid; a source of gas under pressure; a discharge nozzle; pipes connecting said tank, discharge nozzle and source of gas under pressure; a valve connected in said pipes adapted to control the 10 flow of gas from said source of gas under pressure alternately to said tank and said nozzle; a casing connected in said pipes be-

tween said valve and said nozzle; a spring-pressed member in said casing adapted for operation by the spring thereof upon the 15 pressure of gas in said pipes being reduced when the nozzle is open; an alarm device attached to said casing; and means in said tank for forcing a liquid from the latter by pressure of gas in said tank. 20

In testimony whereof I have signed my name to this specification on this 18th day of September A. D. 1919.

WILLIAM J. RUFF.
